HANDLE FOR TROWEL OR THE LIKE

George E. Snyder, Sun Prairie, Wis.

Original design application Feb. 12, 1960, Ser. No. 59,384. Divided and this application Mar. 9, 1962, Ser. No. 69,349

Term of patent 14 years

(Cl. D51—1)

Fig. 1

Fig. 2

Fig. 3

Fig. 4

FIGURE 1 is a top plan view of a handle for trowel or the like embodying my new design;

FIGURE 2 is an elevational view taken from one side thereof, the opposite side being substantially the same;

FIGURE 3 is a bottom plan view thereof; and

FIGURE 4 is an elevational view taken from one end thereof; the opposite end being substantially the same.

The broken line representation of a trowel blade in FIGURES 1 and 2 is for purposes of illustration only.

This application is a division of my co-pending application Serial No. D. 59,384, filed February 12, 1960, now abandoned.

I claim:

The ornamental design for a handle for a trowel or the like, as shown and described.
